US0D1039829S

(12) **United States Design Patent** (10) **Patent No.:** **US D1,039,829 S**
(45) **Date of Patent:** **** Aug. 27, 2024**

(54) **KEYCHAIN HOLDER**

(71) Applicant: **Dongguan Kaishuo Electronics Technology Co., Ltd.**, Dongguan (CN)

(72) Inventor: **Jing Cai**, Dongguan (CN)

(73) Assignee: **Dongguan Kaishuo Electronics Technology Co., Ltd.**, Dongguan (CN)

(**) Term: **15 Years**

(21) Appl. No.: **29/927,709**

(22) Filed: **Feb. 6, 2024**

(30) **Foreign Application Priority Data**

Nov. 14, 2023 (CN) 202330742182.X

(51) **LOC (14) Cl.** **03-01**

(52) **U.S. Cl.**

USPC **D3/207**

Primary Examiner — Steven J Czyz

(57) **CLAIM**

The ornamental design for a keychain holder, as shown and described.

DESCRIPTION

FIG. 1 is a front and bottom perspective view showing of a keychain holder showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures illustrate portions of the keychain holder that form no part of the claimed design.

1 Claim, 8 Drawing Sheets
